DRILLING MACHINE

Walter T. Caldwell, Enid, Okla., assignor to The
George E. Falling Supply Company, Enid,
Okla., a corporation of Oklahoma

Application August 5, 1940, Serial No. 351,502

10 Claims. (Cl. 255—22)

This invention relates to earth drilling machines particularly for drilling relatively shallow holes such as the shot-holes in seismic surveys, and has for its principal object to provide a drilling machine of this character equipped with drill feeding mechanism that is also adapted to serve as an elevator for running in and pulling the drill pipe.

Other objects of the invention are to provide a drilling machine adapted for faster drilling operation; to provide the drilling machine with a drill rotating mechanism having a shiftable drive sleeve to facilitate uncoupling of the drill pipe sections; to provide connection of the drill feeding mechanism with the swivel head; to provide trunnion mounting for the swivel head to facilitate handling of the drill pipe; to provide for ready engagement and disengagement of the swivel head with the feeding mechanism; to provide a rotary driving member mounted upon a single antifriction bearing in such manner that the effective component thrust load on the gear is within the pitch diameter of the bearing or circumferentially of the mean pitch diameter of the gear, thus causing a positive downthrust on all portions of the bearing; and to provide a bearing arrangement wherein the bearing acts as an antifriction hold-down for the rotating members about a vertical axis within the table.

Other objects of the invention are to provide a mast construction wherein the hydraulic cylinders of the feeding mechanism constitute the major part of the mast; and to provide a mast structure wherein the truss legs are utilized as ducts for supplying a hydraulic fluid to the respective ends of the hydraulic cylinders.

In accomplishing these and other objects of the invention, as hereinafter pointed out, I have provided improved details of structure, the preferred form of which is illustrated in the accompanying drawings, wherein:

Fig. 1 is a side elevational view of a drilling machine embodying the features of the present invention, parts of which are shown in section to better illustrate the construction.

Fig. 2 is a detail elevation showing the swivel head in pivoted position as when removing or connecting a section of drill pipe thereto.

Fig. 3 is an end elevation of the machine, showing the swivel head in its lowermost position in full lines and in an upper position in dotted lines.

Fig. 4 is a detail perspective view of the connecting yoke whereby the swivel head is trun-

nionally connected with the hydraulic cylinders of the drill feeding mechanism.

Fig. 5 is a detail perspective view of the swivel head and drill pipe connecting spindle.

Fig. 6 is a plan view of the machine.

Fig. 7 is a horizontal section on the line 7—7 of Fig. 1.

Fig. 8 is a detail view of the drill pipe rotating mechanism, part of which is shown in vertical section to better illustrate the driving sleeve and connection of the swivel head spindle with the drill pipe.

Fig. 9 is an enlarged detail elevation, particularly illustrating connection of the swivel head with the drill feeding mechanism, and showing the drill rotating mechanism in section.

Fig. 10 is a horizontal section through the drill rotating mechanism on the line 10—10 of Fig. 9.

Fig. 11 is a detail perspective view of the driving sleeve.

Referring more in detail to the drawings:

1 designates a drilling machine embodying the features of the present invention, and which includes a motor vehicle 2, such as a truck, having a platform 3 mounted on the frame 4 thereof. The vehicle 2 is equipped with the usual motor (not shown), having driving connection with the rear wheels 5 through a transmission indicated by the dotted lines 6 in Fig. 1. The transmission 30 is provided with power take-off mechanisms 7 and 8 for driving shafts 9 and 10, arranged to respectively operate a drill rotating mechanism 11 through a clutch 12, and a circulating pump 13 through a chain and sprocket drive enclosed in a housing 14. The circulating pump is mounted on the forward end of the platform, while the drill rotating mechanism is mounted at the rear of the platform in spaced relation with the wheels 5.

40 Mounted on the platform, intermediate the drill rotating mechanism and circulating pump, are spaced brackets 15, having pivotal connection as at 16 with a mast structure 17 which is adapted to be moved from a horizontal transport 45 position to a perpendicular drilling position as shown in Fig. 1. The mast 17 includes a pair of hydraulic cylinders 18 and 19 of length approximating the length of the drill pipe sections or stands, and which are located on opposite sides 50 of the drill rotating mechanism as best shown in Fig. 3. The upper ends of the cylinders are connected by a yoke 20, having lateral extensions 21 (as shown in Fig. 6) to the rear of the cylinders for connecting the upper ends of relegs 22. 55 The lower ends of the respective cylinders are

closed by heads 23 and 24 adapted to seat upon the platform, and which have sockets 25 for the lower ends of the relegs. The heads 23 and 24 also have anchoring portions 26 adapted to engage seats 27 on the rear of the platform, and to be secured therein by suitable fastening devices 28, as shown in Fig. 3.

Connected with the upper and lower ends of the relegs are truss legs 29 having portions 30 and 31 diverging from the relegs and intersecting adjacent the pivot 16 to connect with arms 32, also having connection with the relegs. The arms 32 terminate in ears 33 having connection with the pivot 16. The relegs may be connected with the truss legs by suitable girths 34 and cross-bracing, and the respective truss legs are connected by cross-girths 35 to provide a rigid mast construction. The portions 30 and 31 of the truss legs are preferably tubular, as are the cross-girths 35, so that they may be utilized as ducts 36 and 37 for conveying a pressure medium to the respective ends of the cylinders.

The mast is moved to and from its respective positions by a hydraulic jack 38, including a cylinder 39 pivoted to the platform at its lower end and, having a piston therein operably connected with the mast by a rod 40, the rod 40 being connected with one of the truss legs by a pivotal connection 41. The piston rod 40 operates through a suitable stuffing box 42 at the upper end of the cylinder. A pressure medium, such as oil, is delivered to the respective ends of the cylinder through ports 43 and 44 (see Fig. 6) having connection through flexible ducts 45 and 46 with a four-way control valve 47. The control valve 47 is also connected with a duct 48 leading to a tank 49 which is mounted on the platform and adapted to contain a supply of pressure fluid. The supply connection of the valve 47 is connected by a duct 50 with the discharge of a pressure pump 51, having its intake 52 connected with the supply tank 49. A suitable by-pass 53 is provided between the duct 50 and the tank 49, whereby the pressure medium is by-passed from the pump when the piston reaches one or the other ends of the cylinder, the by-pass being controlled by a regulating valve 54 therein.

The pump 51 is geared with a second pump 55 mounted on the platform alongside the pump 51, and both pumps are operably connected with the shaft 10 through a suitable drive connection indicated by the housing 56. The pump 55 also has its inlet connected with the tank 49 through a duct 57, and its discharge connected by a duct 58 with a four-way control valve 59. The duct 58 is connected with the tank 49 by a by-pass 60 having a relief valve 61. The valve 59 has connection through flexible ducts 62 and 63 with the tubular cross-girths on the respective sides of the pivot 16, as clearly shown in Fig. 1, whereby pressure medium is supplied through the truss legs to the respective ends of the hydraulic cylinders for a purpose later described. The valve 59 also has connection by a duct 64 with the supply tank 49.

Slidably mounted in the respective hydraulic cylinders, as shown in Figs. 1 and 9, are pistons 65 to which are connected rods 66 having their upper ends extending through stuffing boxes 67 carried by the connecting yoke 20. The piston rods 66 have their free ends connected by a cross-bar 68 as shown in Fig. 3. Connected with the cross-bar, and depending therefrom in parallel relation with the hydraulic cylinders, are reins

69 slidable through bearings 70 in the yoke 20 and having their lower ends 71 connected to a cross-bar 72.

As shown in Fig. 4, the cross-bar 72 includes a substantially semicircular yoke portion 73, having laterally extending arms 74 to which the ends of the reins 69 are connected. The ends of the arms terminate in sleeves 75 and 76 slidably mounted on the respective cylinders. It is thus obvious that when pressure medium is admitted to the lower ends of the cylinders, the pistons are moved upwardly to carry the bar 72 toward the upper ends of the cylinders, and when the pressure medium is admitted to the top of the cylinders, the bar 72 is moved downwardly to the lower ends of the cylinders. The mechanism thus described constitutes an elevator movable upon the hydraulic cylinders to raise and lower the swivel head 77.

The swivel head 77 is best shown in Fig. 5 and includes a body 78 swivelly mounting a nipple 79, having its upper end connected by an L-fitting 80 with a flexible duct 81 leading to the discharge connection of the circulating pump 13, as in conventional rotary drilling practice. The lower end of the nipple connects with a cylindrical shank 82 through a polygonal-shaped head 83. The head 83 also includes a collar 84 for a purpose later described. The lower end of the shank 82 has a tool joint pin 85 forming a shoulder 86 with the cylindrical body of the shank and having a tool joint thread 87. Extending laterally from opposite diametrical sides of the swivel body 78 are trunnions 88 and 89 having flattened sides 90, and arcuate upper and lower edges 91 and 92. The trunnions are thus of greater height and width so as to form keys in retaining the swivel head on the bar 72, and to permit removal thereof as later described.

In order to connect the swivel head with the bar 72, the bar has ears 93 and 94 provided with bearing openings 95 and 96 corresponding to the arcuate edges of the trunnions 88 and 89. Intersecting the bearing openings are lateral slots 97 and 98 having width corresponding to the narrower width of the trunnions so that when the swivel head is moved to a substantially horizontal position the trunnions will pass readily through the slots 97 and 98 and enter the bearing openings 95 and 96. Then when the swivel head is moved to vertical position, the trunnions oscillate in the bearing openings to be retained therein as long as the swivel head is in vertical position.

The rotating mechanism 11 is best illustrated in Figs. 9 and 10, and includes a cylindrical housing 99 fixed to the platform in alignment with the swivel head. Rotatably mounted in the housing 99, on an antifriction bearing 100, is a rotary member including a sleeve-like hub 101 having an annular flange 102 for seating a ring gear 103 which meshes with a driving pinion 104 fixed to the driven shaft 105 of the clutch 12, previously mentioned. The top of the housing is closed by a suitable cap 106 which forms a part of the rotary member and has a depending collar portion 107 threadedly connected with the upper end of the hub 101. The bore of the collar is tapered, as at 108, to cooperate with an upper conical portion 109 of the sleeve-like hub 101 to seat a tapered driving bushing 110 therein, the lower portion of the sleeve-like hub and bushing being substantially cylindrical, as shown in Fig. 9. The driving bushing 110 has laterally extending ears 111 en-

gaged in notch-like recesses 112 of the collar portion 107. The bushing is retained in the bore of the hub by plates 113 fixed to the cover 106 by fastening devices 114. The drive bushing 110 has a bore 115 conforming in diameter to the drive sleeve 116, so that the drive sleeve is freely slideable therein but is drivingly engaged therein through rod-like keys 117 engaged in substantially semi-cylindrical sockets 118 formed in the inner surface of the bore, and in similarly shaped ways 119 formed in the outer periphery of the drive sleeve, as clearly shown in Fig. 9. The upper portion of the drive bushing is counterbored to a larger diameter to form a spring seat 120, having a coil spring 121 engaged over the drive sleeve and having its upper end bearing against an annular collar 122 at the upper end of the sleeve, and which is adapted to be engaged by the flange-like collar 84, previously mentioned, and for a purpose later described. The drive sleeve is of greater length than the drive bushing, and carries a stop collar 123 on the lower end thereof which normally engages against the lower end of the drive bushing. The bore of the drive sleeve is of polygonal-shape, as indicated at 124, to conform to the cross-sectional shape of the drill rod 125.

In the illustrated instance, the drill rod is shown of rectangular cross-section, although other shapes may be used without departing from the spirit of the invention. The drill pipe 125 has an axial channel 126, registerable with the flow channel 127 through the shank 82 when the socketed end 128 is connected with the pin of the shank as shown in Fig. 9.

The bearing 100 includes an outer race 100' that is rigidly clamped within the housing 99 by the bottom plate 99' so that the bearing is positively positioned to carry the weight of the load and to take thrusts acting in both up and down directions. The bearing also includes an inner race 100'' that is clamped against the ring gear 103 by the heads of bolts 103' so that it is rigidly carried by the rotary unit. It is therefore obvious that this single bearing serves the purpose of a hold-down ring to resist upward thrusts, and also supports the downwardly acting loads. Attention is further directed to the fact that the diameter of the bearing is of a size relative to the ring gear so that the component gear load, that is the effective component thrust load on the ring gear, is within the pitch diameter of the bearing, thus causing a positive down thrust on all portions of the bearings.

Assuming that the drilling rig is at a drilling location, the mast is moved to perpendicular position by adjusting the valve 47 so that pressure medium is admitted to the lower end of the cylinder 39. As the pressure medium forces the piston to the top of the cylinder, the mast is moved on the pivot 16 to perpendicular position, after which the fastening devices 28 are adjusted to anchor the lower ends of the cylinders and retain the mast in perpendicular position. The swivel head and the carrying yoke therefor are at the lower position shown in Fig. 2, and the swivel head carries only the shank 82. A stand of drill pipe is connected with the threaded pin of the shank. This is readily effected by supporting the box end of the drill pipe in registry with the pin and locating the shank by means of a suitable wrench engaged with the polygonal-shaped head 83 thereof, while the drill pipe is being held by another wrench. If desired, the swivel head may be completely withdrawn from

its supporting connection with the cross-bar so that connection of the drill pipe may be made on the ground. In this instance the drill pipe carrying the head will be moved into a position so that the trunnions 88 and 89 will enter the slots 97 and 98. The valve 59 is then manipulated so that pressure medium is delivered by the pump 56 to the lower ends of the cylinders. The pistons are then moved upwardly in the cylinders to raise the rods 69, carrying the cross-bar 72 therewith toward the upper ends of the cylinders. The stand of drill pipe, being connected with the shank 82, is carried with the cross-bar to a position so that the lower end thereof depends over the bore of the drive sleeve. The valve 59 is again adjusted so that the pressure medium is released from the bottom of the cylinders into the tank, and the lower end of the drill pipe is guided through the bore of the sleeve. After the lower end of the drill pipe has passed through the sleeve, the box thereof may be connected to the pin of the drill bit and the drilling operation started.

When the clutch 12 is engaged, the driving sleeve is rotated through the gears 103 and 104, and drive bushing. Upon adjusting the valve 59 so that pressure is admitted to the top of the cylinders, a feeding pressure is applied to the bit to promote the drilling action of the bit. When the swivel head reaches its lower position, the collar 84 engages the collar of the driving sleeve. In this position the joint of the drill pipe is located within the drive sleeve as shown in Fig. 9, so that it is in driving engagement therewith. As the drilling proceeds, the drive sleeve is moved downwardly within the bushing so that the threaded connection is carried below the housing 99, as shown in Fig. 9. It is then necessary to apply another joint or stand of drill pipe to the drilling string in the bore-hole. This is effected by holding the upper end of the drill pipe with a suitable wrench, applying the wrench to the polygonal head of the shank, and rotating the shank 82 within the bore of the drive sleeve. Since the shank is of cylindrical character, it may turn freely with respect to the drill pipe, as the joint unthreads and the swivel head is raised by admitting pressure medium to the lower ends of the hydraulic cylinders. The drive sleeve follows the shank 82 by reason of the spring 121 which has been previously compressed. The lower end of the sleeve thus clears the joint when the threads are completely disengaged, and the collar 123 again engages the lower end of the drive bushing. Another stand of drill pipe is suspended over the rotating mechanism in the same manner as above described, and the end thereof lowered through the bore of the drive sleeve. The suspended stand of drill pipe, upon being guided through the bore, engages the box of the stand in the bore-hole. Since the drive sleeve is free of the stand in the bore-hole, the suspended stand may be rotated so as to connect it with the stand in the hole. After connection the drilling operation proceeds as above described.

Additional stands are added from time to time until the desired depth of hole is reached. The stands are successively withdrawn from the bore-hole by reversing the running in operation. For example, in removing the first stand, pressure medium is admitted to the bottom of the hydraulic cylinders to raise the swivel head and lift the drill pipe one stand so that the joint comes below the rotating mechanism. The stand projecting from the hole is supported by a suit-

able spider (not shown), whereupon the upper stand may be unthreaded as in conventional practice, and raised to a position so that the lower end clears the upper part of the rotating mechanism. The pressure medium is then released from the lower ends of the cylinders so that the drill pipe may be lowered to the ground. Upon guiding the lower end of the pipe away from the drilling position, and continuing lowering the upper end, it is readily moved to a horizontal or reclining position so that the joint may be readily disconnected from the shank of the swivel head.

From the foregoing it is obvious that I have provided a drilling mechanism which is of simple construction and adapted for drilling shallow holes in faster time and with less equipment than is ordinarily employed in conventional drilling rigs, since the hydraulic feeding mechanism is utilized as an elevator for handling the drilling string.

What I claim and desire to secure by Letters Patent is:

1. In a drilling machine, drill rotating means including a drive bushing, a drive sleeve having sliding keyed connection with the drive bushing, a swivel head, a stem carried by the swivel head and having threaded connection with a drill rod extending through the drive sleeve, and means on the stem engageable with the drive sleeve when the stem enters the drive sleeve to shift said drive sleeve in the bushing and maintain driving connection with the drill rod when the drill rod is moved below said bushing, said stem being of a size and shape to rotate in said drive sleeve for effecting disconnection of the drill rod.

2. In a drilling machine, drill rod rotating means, a drive bushing carried by said rotating means, a drive sleeve having sliding keyed connection with the drive bushing, a spring between the drive sleeve and drive bushing to yieldably retain said drive sleeve in elevated position with respect to the drive bushing, a drill rod extending through the drive sleeve, means supporting the drill rod, and means on said supporting means engageable with the drive sleeve to depress said sleeve against action of said spring, whereby driving engagement of the drill rod is retained with the drive sleeve after the drill rod passes said drive bushing upon lowering of the drilling string, said stem being of a size and shape to rotate in said drive sleeve for effecting disconnection of the drill rod.

3. In a drilling machine, drill rod rotating means, a drive bushing carried by said rotating means, a drive sleeve having sliding keyed connection with the drive sleeve, a spring between the drive sleeve and drive bushing to yieldably retain said drive sleeve in elevated position with respect to the drive bushing, a drill rod extending through the drive sleeve and drive bushing, drill rod raising and lowering means, a swivel head connected with said raising and lowering means, a stem carried by said swivel head and having threaded connection with said drill rod, and drive sleeve engaging means carried on the stem to depress said drive sleeve against action of the spring when the stem enters the drive sleeve for maintaining driving connection of the drive sleeve with the drill rod after the threaded connection has passed through the drive bushing upon lowering the drill rod, said stem being of a size and shape to rotate in said drive sleeve for effecting disconnection of the drill rod from said stem.

4. In a drilling machine, drill rod rotating means, a drive bushing carried by said rotating means, a drive sleeve having sliding keyed connection with the drive bushing, a spring between the drive sleeve and drive bushing to yieldably retain said drive sleeve in elevated position with respect to the drive bushing, a drill rod extending through and having driving engagement with the drive sleeve, drill rod raising and lowering means, a swivel head pivotally mounted on said raising and lowering means, a shank carried by the swivel head and having free rotative movement in the drive sleeve, said shank having threaded connection with the drill rod, and a stop collar on said shank engageable with the drive sleeve to depress the drive sleeve in the drive bushing and maintain driving connection with the drill rod until said threaded connection has cleared the rotating means.

5. In a drill rod rotating mechanism, a gear housing, a drill rod rotating means in the housing including threadedly engaged upper and lower rotating members, a drive bushing having laterally projecting means connecting the drive bushing for rotation with said members, a lateral annular flange on the lower member, a ring gear fixed to the flange of said lower member, and an antifriction bearing including an outer race having fixed connection with the gear housing and an inner race having fixed support relative to the ring gear and having antifriction bearing members between said races, said bearing being of a size relative to the ring gear so that it is located circumferentially of the mean pitch diameter of said gear.

6. In a drill rod rotating mechanism, a gear housing, a drill rod rotating means in the housing including threadedly engaged upper and lower rotating members, a drive bushing carried by said members, a ring gear fixed to the lower member, an antifriction bearing including an outer race having fixed connection with the gear housing and an inner race having fixed support relative to the ring gear and having antifriction bearing members between said races, said bearing being of a size relative to the ring gear so that it is located circumferentially of the mean pitch diameter of said gear, a drive sleeve having sliding keyed connection with the drive bushing, a stem having threaded connection for a drill rod adapted to be extended through the drive sleeve, and means on the stem engageable with the drive sleeve when the stem enters the drive sleeve to fasten said drive sleeve in the bushing and maintain driving connection with the drill rod when the drill rod is moved below said bushing, said stem being of a size and shape to rotate in said drive sleeve for effecting disconnection of the drill rod.

7. In a drilling machine, drill rod rotating means, a drive sleeve having a driven sliding connection relative to said rotating means, a swivel head, a stem carried by the swivel head and having a connection for a drill rod adapted to be extended through the drive sleeve, and means on the stem engageable with the drive sleeve when the stem enters the drive sleeve to shift said drive sleeve relative to the rotating means and maintain driving connection with the drill rod when the drill rod is in one position, said stem being of a size and shape to rotate in said drive sleeve for effecting disconnection of the drill rod.

8. In an apparatus of the character described, 75 a gear housing, a drill pipe rotating member in

the gear housing, a ring gear fixed to the drill pipe rotating member and enclosed in the gear housing, a driving gear meshing with the ring gear, an antifriction bearing rotatably supporting the drill pipe rotating member in the gear housing and having inner and outer races and antifriction members between said races, said bearing being of a diameter relative to the ring gear so that the effective thrust load on the ring gear is within the pitch diameter of said bearing, said housing having a shouldered recess receiving the outer race and forming a stop therefor in one axial direction, means for clamping said outer race against said stop to prevent movement of the outer race in an axial direction within the housing, and means clamping the inner race in fixed axial relation to the ring gear.

9. In an apparatus of the character described, a gear housing, a drill pipe rotating member in the gear housing, a ring gear fixed to the drill pipe rotating member and enclosed in the gear housing, a driving gear meshing with the ring gear, a single antifriction bearing rotatably supporting the drill pipe rotating member in the gear housing and having inner and outer races and antifriction members between said races, said bearing being of a diameter relative to the ring gear so that the effective thrust load on

the ring gear is within the pitch diameter of said bearing, said housing having a shouldered recess receiving the outer race and forming a stop therefor in one axial direction, means for clamping said outer race against said stop to prevent movement of the outer race in an axial direction within the housing, means clamping the inner race in fixed axial relation to the ring gear, and a turntable carried by the rotating member whereby loads on the turntable are supported by said single antifriction bearing.

10. A drill rod rotating mechanism including, a housing having an opening in the upper end, drill rod rotating means in the housing including threadedly engaged upper and lower rotating members, said upper member having a cap closing the upper end of the housing, said lower member having a laterally extending annular flange provided with an upper gear engaging face, a ring gear fixed in seating engagement with said face, an antifriction bearing between said flange and the housing for supporting the drill rod driving means from axial movement within the housing, and a drill rod drive bushing carried by said threadedly engaged rotating members.

WALTER T. CALDWELL.
